COMBINED COMPARTMENTED TRAY AND FOOD SERVING INSERTS THEREOF

Willis A. Stageberg, St. Louis Park, Minn., assignor, by
mesne assignments, to Plastics, Inc., St. Paul, Minn.,
a corporation of Delaware

Filed Apr. 18, 1968, Ser. No. 11,515

Term of patent 14 years

Int. Cl. D7—01

U.S. Cl. D44—10

FIG. 1

FIG. 2

FIG. 3

FIG. 4

FIG. 5

FIG. 6

FIG. 7

FIGURE 1 is a top plan view of the combined compartmented tray and food serving inserts thereof showing minute design;

FIGURE 2 is a bottom plan view;

FIGURE 3 is a sectional view on the line 3—3 of FIGURE 1;

FIGURE 4 is an enlarged scale top plan view of the central food serving insert;

FIGURE 5 is a bottom plan view of the insert;

FIGURE 6 is an enlarged scale sectional view through the central compartment, with the food serving insert therein; and

FIGURE 7 is a side elevational view of the tray with the food serving inserts therein.

I claim:

The ornamental design for a combined compartmented tray and food serving inserts thereof, as shown.
